UNITED STATES PATENT OFFICE.

LOUIS COTÉ, OF ST. HYACINTHE, QUEBEC, CANADA.

MACHINE FOR NAILING ON THE HEELS OF BOOTS AND SHOES.

SPECIFICATION forming part of Letters Patent No. 310,562, dated January 13, 1885.

Application filed September 20, 1884. (No model.)

To all whom it may concern:

Be it known that I, LOUIS COTÉ, of the city of St. Hyacinthe, in the county of St. Hyacinthe, Province of Quebec, Dominion of Canada, have invented new and useful Improvements in Machines for Nailing on the Heels of Boots and Shoes; and I do hereby declare that the following is a full, clear, and exact description of the invention.

10 This invention has reference to improvements in a machine for nailing the heels and soles of boots and shoes together, to enable the same to work with greater rapidity, while the operator is enabled to adjust the position 15 of the heel upon the sole with greater exactness than when operating with the machine as constructed before my present invention. By my invention an operator can, with less bodily labor and in the same time required 20 by the old machine to nail on two heels, with my improved machine nail on five or six heels, thus making a large saving in the price of the labor to be paid for this operation, and in large establishments the cost and room. required for, say, three machines, to do the work 25 of one of my improved machines.

The features which form my invention will be hereinafter fully set forth and described.

In the drawings hereunto annexed, similar 30 letters of reference indicate like parts, and Figure 1 is a front elevation of a boot and shoe heel nailing-on machine in which are embodied the improvements forming my present invention. Fig. 2 is a side elevation of the 35 machine shown in Fig. 1. Fig. 3 is a plan of that part of the machine which is situated above the line α , Fig. 2. Fig. 4 is a horizontal section on line α , Fig. 2. Fig. 5 is a plan of the treadle for operating rapidly the presser-plate 40 or follower-block a of the machine. Fig. 6 is a diagram showing the manner in which a 45 boot or shoe is held by the machine shown in Figs. 1 and 2 while the nailing of the heel to the sole is accomplished.

As in the machine shown in the drawings a considerable portion of it is old, it becomes necessary for the clear understanding of my invention to enter at some length into a particular description of the parts that are old 50 as well as those that are new, also into a general description of how the machine has been heretofore operated.

Letter A is a lower frame, which is firmly

attached on the floor, &c., in the ordinary manner. To this is attached the upper frame, B. 55

On the frame B is secured, by bolts and nuts C, a standard, D, within which a plunger, E, and rod, F, are situated, as shown in Fig. 6. The standard is provided with a head, G, having within it vertical or nearly vertical holes 60 H, situated in the positions in which the nails are required to pass through the sole I into the heel K. The plunger E is provided with "fork" 65 projections L, one for each of the holes H, in which they freely slide, so that when the plunger and projections L are moved downward (from the position they are shown in Fig. 6) a sufficient amount of the nails M may be placed in the holes H.

As shown in Fig. 6, the plunger E is in a 70 midway position, showing a nail, M, in a partly-driven condition, or as if the plunger had risen from about the level of the line α , and when the plunger has risen to within a short distance of touching the head G the nail will 75 have been completely driven "home" into the sole and heel.

a is a presser-plate or follower-block, which is brought down with considerable force upon the heel K, and tightly holds the sole and 80 heel upon the head G while the nails are being driven.

Fig. 6 so clearly shows how the sole and heel are held that no further explanation is required in this respect.

The rod F extends below the standard D, as shown in Fig. 1, and is operated by the following mechanism: To the under side of the frame B are attached two brackets, b, in which which is journaled a revolving shaft, c, provided with a disk, d, at its front end. Upon this disk projects a crank-pin, e, which operates a pitman, f. The end of the pitman does not come in contact with the end of the rod F; but whenever it is desired to operate the rod F a sliding block is interposed between the end of the rod F and the end of the pitman f, the said block being of such thickness that the desired portion of the stroke of the pitman will be imparted to the rod F. This said sliding block is operated by the handle s'. On the shaft c is secured a gear-wheel, g, which intermeshes with a pinion, h, secured on the driving-shaft i, carried, journaled, and revolving in lugs k, formed on the frame A. 95

l is a fly-wheel secured on the shaft i, and 100

105

m are ordinary pulleys for the transmission of power by a belt in the ordinary way to revolve the shaft *i*.

Now, all that has been hereinabove described 5 is old or substantially old, and the above description is given for the purpose of conveying a clear knowledge of the state of the machine at the time of my invention, and to complete the description of what is old.

10 The object of my invention is to provide the machine with a means of rapidly operating the follower-block *a*, and, further, that such means shall be automatic in so far as the raising of the follower-block *a* is concerned after the operation of nailing the sole and heel together 15 has been accomplished.

a' is a socket or guide in which moves a slide-bar, *b'*, provided with any suitable feather or key for keeping the slide-bar from turning 20 around, while it is free to slide up and down within the socket or guide *a'*. On the lower end of the slide-bar a head, *c'*, is formed, and, as shown in Fig. 1, to the lower side of this head the follower-block or presser-plate *a* is 25 secured by a dovetail recess in the head *c'* and corresponding dovetail projection on the follower-block or presser-plate *a*. On the upper extremity of the slide-bar *b'* a double eye, *d'*, is formed, and on the socket *a'* an upwardly-extending arm, *e'*, is formed. This terminates 30 in a horizontal eye, *f'*, through which the screwed neck of a double eye, *g'*, passes.

h' are "jam-nuts," for securing the double eye *g'* in position, and for adjusting the height 35 of the same. Between the double eyes *d'* and *g'* a toggle-joint, *i' i'*, is attached, in the ordinary way, so that by the adjustment of the height of the double eye *g'* that of the toggle-joint *i' i'*, slide-bar *b'*, head *c'*, and follower-block *a* are also adjusted to give the proper 40 distance between the follower-block *a* and head *G* for properly compressing the sole and heel between them when the toggle-joint is in (or nearly in) its most extended position.

45 The frame *B* is provided with upward and backward extending arms *B'*, which unite together at their upper extremity, and to them is secured a double eye, *k'*, between which and the center-pin *l'* of the toggle-joint *i' i'* is attached the toggle-joint *m' m'*. (See Fig. 2.)

Again, to the center-pin *n'* of the toggle-joint *m' m'* is attached the double eye *o'*, formed upon the upper end of the connecting-rod *p'*, which said connecting-rod passes down through the 55 open space in the frame *B*, as will be clearly understood by reference to Figs. 2 and 4. The lower end of the connecting-rod is also provided with a double eye, *q'*, which connects in the ordinary way with the treadle-bar *a'* of a 60 treadle, *B'*, of which *b'* is the foot-plate. The bar *a'* is made in one with a sleeve, *c'*, which is placed and pivoted on a shaft, *d'*, carried in brackets *e'*, one of which is attached at the back on each side of the frame *A*. The said 65 sleeve *c'* is also provided with a second arm, *f'*, upon which is secured a counterbalance-weight, *g'*.

*h*² is an adjustable contrivance by which the descent of the counterbalance-weight *g*² may be governed at pleasure.

The contrivance *h*² is only one modification of a great number that may be applied to the counterbalance-weight or to the arm *f*² upon which it is secured, and as such contrivances are well known and understood it is considered unnecessary to enter into any description of them.

The adjustable contrivance *h*² is not necessary, although very convenient and suitable, because the descent of the counterbalance-weight *g*² would be limited by the head *c'* being drawn up so high that it would bear against the under side of the socket *a'*, and to prevent the "jar" which would be caused to the machine if this were done with force when the machine is working quickly at full stroke, an elastic washer, *h'*, is provided. This is slipped over the slide bar, *b'*, before it is put in place in the socket or guide *a'*.

The operation of the machine is as follows: 90 The counterbalance-weight having raised the treadle *B'*, connecting-rod *p'*, and moved the toggle-joints *m' m'* and *i' i'* to the positions indicated by dotted lines, thus causing the slide-bar *b'*, head *c'*, and presser-plate or follower-block to be raised the amount of the distance between the lines 1 and 2, thus giving room for a boot and heel to be placed on the head *G*, in the position shown in Fig. 6. The holes *H* are then provided with nails, and 100 the boot or shoe and heel placed in position on the head *G*, whereupon the foot of the operator is placed upon the foot-plate *b'* and the preponderance of weight of the counterbalance-weight overcome with sufficient force to 105 bring the follower-block or presser-plate *a* down upon the heel, as shown in Fig. 6, and tightly compress or "jack" the heel and sole between the head *G* and follower-block or presser-plate *a*. The mechanism for driving 110 the nails through the sole and into the heel is then put in motion by actuating the sliding block, hereinbefore mentioned, by the handle *s'*. As soon as the nails are driven the foot 115 of the operator is removed from the foot-plate *b'*, and the preponderance of weight of the counterbalance-weight causes the follower-block or presser-plate *a* to rise by the movement of the working parts connected to the treadle to the positions shown in dotted lines. The holes *H* are again provided with nails, 120 ready for the next boot or shoe. By the adjustment of the double eye *g'* the height in stroke of the follower-block or presser-plate is adjusted to what is required for properly 125 pressing or "jacking" any particular thickness of sole and height of heel. This is done by the adjustment of the nuts *h'*.

Although the toggle-joint *i' i'* is represented as actuated by a second toggle-joint, *m' m'*, yet a bell-crank might be used, because the one arm of the bell-crank and the link connecting it to the toggle-joint would be the equivalent of the two parts of the toggle-joint *m' m'*.

What I claim and wish to secure is as follows:

1. The combination, in a sole and heel nail-
ing machine, of the standard D, provided
5 with plunger E, having projections L, and the
rod F, head G, having nail-receiving holes H,
said holes also receiving and guiding said pro-
jections L, as shown and described, follower-
block a, slide-bar a', toggle-joint i' i', and a
10 device for actuating the said toggle-joint by
means of a treadle, B³, and counterbalance-
weight g², with said treadle B³, and counter-
balance-weight g², as described, the whole con-
structed and arranged substantially as shown
15 and described.
2. The combination, in a sole and heel nail-
ing machine, of the standard D, provided
with plunger E, having projections L, and the
rod F, head G, having nail-receiving holes H,
20 said holes also receiving and guiding said pro-

jections L, as described, follower-block a,
slide bar a', toggle-joints i' i' and m' m', connect-
ing-rod p', and treadle B³, the whole con-
structed and arranged substantially as shown
and described.

3. The combination, in a sole and heel nail-
ing machine, of the standard D, provided
25 with plunger E, having projections L, and the
rod F, head G, having nail-receiving holes H,
said holes also receiving and guiding said pro-
jections L, as shown and described, follower-
block a, toggle-joints i' i' and m' m', connect-
ing-rod p', treadle B³, and counterbalance-
weight g², the whole constructed and arranged
30 substantially as described and shown.
